Primary Examiner — Lauren D McVey(74) *Attorney, Agent, or Firm* — Knobbe Martens Olson & Bear LLP(57) **CLAIM**

The ornamental design for a monitor arm, as shown and described.

DESCRIPTION

FIG. 1 is an isometric view of the monitor arm embodying the new design;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken lines are directed to environment. The broken lines form no part of the claimed design.

1 Claim, 7 Drawing Sheets
